UNITED STATES PATENT OFFICE.

FRANCIS P. SINN, OF PALMERTON, PENNSYLVANIA, AND FREDERIC E. PIERCE, OF NEWARK, NEW JERSEY, ASSIGNORS TO THE NEW JERSEY ZINC COMPANY, OF NEW YORK, N. Y., A CORPORATION OF NEW JERSEY.

SCOOP-CAR.

1,071,104.

Specification of Letters Patent. Patented Aug. 26, 1913.

Application filed May 27, 1911. Serial No. 629,856.

To all whom it may concern:

Be it known that we, FRANCIS P. SINN and FREDERIC E. PIERCE, citizens of the United States, residing at Palmerton, county 5 of Carbon, State of Pennsylvania, and Newark, county of Essex, State of New Jersey, respectively, have invented certain new and useful Improvements in Scoop-Cars; and we do hereby declare the following to be a full, 10 clear, and exact description of the invention, such as will enable others skilled in the art to which it appertains to make and use the same.

The object of the invention is to provide a 15 convenient structure embodying a scoop and a motor-impelled carriage or truck transporting and coöperating with the scoop, and peculiarly appropriate actuating mechanism therefor, with the end in view of providing 20 an extremely simple and effective device designed to underrun by progression, lift, transport and discharge ash or other materials.

The invention consists in so mounting a 25 scoop upon a motor-impelled wheeled truck that it may be positioned to underrun, by forward movement of the truck, a heap of the material to be handled, and may then be lifted and leveled clear for transportation, 30 and subsequently tilted for discharge; and in providing the motor driven mechanism of the peculiarly appropriate design herein-after described for actuating the scoop in a simple and direct manner under complete 35 control.

An embodiment of this invention in a 40 scoop car for transporting ash from gas producers to any desired destination is illustrated in the accompanying drawing in

Figure 1, represents a plan view; Fig. 2, represents a side elevation partly in section, on line 2—2 of Fig. 1; Fig. 3 represents a cross section on line 3—3 of Fig. 1, with 45 outline of ashpit in which the car operates, and Fig. 4, represents a diagrammatic view, in which the scoop and its actuating crank, connecting rod and latching device are shown at their essential positions.

50 Referring to the drawings, a truck body A of steel construction is mounted in the usual way upon wheels B, the rear wheels B being geared in any suitable way to a driv-

ing motor C suspended from the truck body. A second motor D, for actuating the scoop, 55 is mounted on the truck body A and its pinion E drives a speed reducing train of gears F, F, F, F, G. The gear G is fast upon and drives a shaft H running in bearings I upon the ends of which shaft cranks 60 J, J, are mounted in the same radial plane. Connecting rods K, K, connect the cranks J, J, with a scoop L and are securely pivoted upon the rear wall of said scoop. The scoop L is linked to the forward end of the 65 wheeled truck being trunnioned at M, M, upon tilting arms N, N, mounted on shaft O, journaled in the truck body A at its extreme forward end the arms and shaft forming a 70 rocking frame or link. The scoop L is prevented from tilting farther back on arms N, N, than its position shown in Fig. 2 by stops P, P, upon its side walls abutting the arms N, N. The rocking frame consisting of 75 the arms N, N, and shaft O is normally locked in the position shown in dot and dash lines in Fig. 4 by latches Q, Q, actuated through the links R, R, connected to the levers S, S, fast on a rocking shaft T, by the action of a weight U on said shaft; and the latches are 80 released when the end of the rear crank J, going up, strikes and tilts a trigger V which actuates slotted links W to engage a pin on a lever X fast on shaft T, and rock said shaft and its before-mentioned connecting 85 parts so as to throw said latches to the full line position in Fig. 4. When the latches Q, Q, release the rear ends of the arms N, N, the cranks J, J, moving upward immediately force the scoop L forward and downward 90 to the lower position shown in Fig. 2 and in full lines in Fig. 4, and the rear ends of the arms N, N, hold the latches back as shown until such time as the arms N, N, are returned to their upper position, when 95 the weight U will throw the latches forward locking the arms N, N, again in their upper position. When the trigger V is tilted by the downward stroke of the rear crank J it does not operate to release the latches owing 100 to the length of the slot in link W.

A cab is provided at the rear end of the truck body A for the operator and is provided with the usual controllers (not shown) for the motors C and D, and a connection 105 X' for a brake wheel, within easy reach of

the operator. A trolley Y mounted upon the cab conducts current to the car from any suitable source as trolley wires or rails.

The operation is as follows: The scoop L 5 being in the position shown in dot and dash lines in Fig. 4 the operator drives the car to within a short distance of the material to be moved and then operates the controller of the motor D to drive the crank J counter clockwise from the position *a* to position *b*, (see Fig. 4). The near crank J trips the trigger V at its start releasing arms N by the drawing back of the latches Q, and the further movement of the cranks J to *b* carries the scoop and arms N to the lower position shown in full lines in Fig. 4. Motor C is then brought into play and the truck is run forward causing the scoop in this position to underrun the ash or other material 20 and be filled therewith. Motor D is then reversed and the cranks J returned clockwise to position *a* drawing back and lifting and leveling the scoop L, with its load, and arms N, clear of the track and into the position first named where the latches Q engage the arms N, by the fall of weight U. The car is then run to a discharge pit or trestle where the motor D is again set in motion to drive the cranks J clockwise from position *a* to position *c*, and as the trigger V does not release the latches during this operation, the arms N remain locked and the scoop L is tilted thereon to the position of discharge shown in dotted lines in Fig. 4 35 and its load discharged. A further movement of the cranks J clockwise from *c* to *a* tilts the scoop L back to the first position named, and as the latches Q are not released by the trip of trigger V in this direction, 40 the several parts are brought back to their position of travel and the car may be driven back to the heap of material and the same operation repeated.

It is obvious that various changes may be 45 made in the details of construction and arrangement without departing from the spirit of this invention.

Having thus described our invention what we claim is:

50 1. In apparatus of the class described, the combination of a body, a rocking frame pivoted upon the forward end of said body, a scoop trunnioned upon said frame and movable therewith to an upper and a lower position, means for locking the frame in the upper position, and an actuator on said body connected directly to said scoop to move the said scoop with said frame to and from said upper and lower positions when 55 said frame is free, and tilt said scoop on said frame when the latter is locked in its upper position.

60 2. In apparatus of the class described, the combination of a body, a rocking frame pivoted upon the forward end of said body, a

scoop trunnioned upon said rocking frame and movable therewith to an upper and a lower position, a lock designed to secure said frame in its upper position, a crank journaled on said body, and a connecting rod directly connecting said crank and said scoop to move, by the angular movement of said crank, the said scoop with said frame to and from said upper and lower positions when said frame is free and tilt the scoop on the frame when the latter is locked in its upper position.

3. In apparatus of the class described, the combination of a body, a rocking frame pivoted upon the forward end of said body, a scoop trunnioned upon said rocking frame and movable therewith to an upper and a lower position, an automatic latch adapted to lock said frame in said upper position, a crank journaled on said body, a manually controlled power drive for said crank in both directions of rotation, a release for said latch actuated by the rotation of said crank in one direction only, a connecting rod directly connecting said crank on said scoop to move said scoop with said frame to said lower position by a continued movement of said crank in that direction which has released said latch, the connecting rod serving also to move the scoop to said upper position and tilt it in said upper position by the movement of said crank in the counter-direction to that which releases said latch.

4. In apparatus of the class described, the combination of a body, members pivoted upon the forward portion of said body, a scoop trunnioned upon said members and movable therewith to an upper and a lower position, a latch adapted to retain said members in their upper position, a crank upon said body, a connecting rod connecting said scoop and said crank, the whole organized to effect, by the angular movement of said crank, a movement of said scoop and said members from their lower to their upper positions and vice versa, when said members are free, and effect a damping of said scoop upon its trunnions when said members are latched in their upper positions.

5. In apparatus of the class described, a body, arms N pivoted to the forward end of the body, a scoop L trunnioned upon said arms, cranks J mounted to revolve on said body, and connecting rods K pivoted to the scoop and to the cranks; substantially as described.

6. A scoop car comprising a motor impelled wheeled truck, a rocking frame pivoted upon the forward end of said truck, a scoop trunnioned upon said rocking frame and adapted to assume therewith a lower and an upper position, means for locking said frame in said upper position, and an actuator on said truck connected directly to said scoop to move the same with said frame

to and from said upper and lower positions when said frame is free and tilt said scoop on said frame when the latter is locked in said upper position.

- 5 7. A scoop car comprising a motor impelled wheeled truck a rocking frame pivoted upon the forward end of said truck, a scoop trunnioned upon said rocking frame and adapted to assume therewith a lower 10 and an upper position, means for locking said frame in said upper position, a crank journaled on said truck and a connecting rod directly connecting said crank and said scoop to move, by the angular movement of 15 said crank, said scoop with said frame to and from said upper and lower positions when said frame is free and tilt the scoop on the frame when the latter is locked in its upper position.
- 20 8. A scoop car comprising a motor impelled wheeled truck, a rocking frame pivoted upon the forward end of said truck, a scoop trunnioned upon said rocking frame and adapted to assume therewith a lower 25 and an upper position, an automatic latch adapted to lock said frame in said upper position, a crank journaled on said truck, a manually controlled power drive for said crank in both directions of rotation, a release for said latch actuated by the rotation 30 of said crank in one direction only, a connecting rod directly connecting said crank and said scoop to move said scoop with said frame to said lower position by a continued 35 movement of said crank in that direction which has released said latch, the connecting rod serving also to move the scoop to said upper position and tilt it in said upper position by the movement of said crank in the 40 counter direction to that which releases said latch.
9. A scoop car comprising a wheeled truck, a motor suitably geared to the wheels of said truck for propelling the same, members pivoted upon the forward portion of 45 said truck, a scoop trunnioned upon said members and adapted to be moved therewith to upper and lower positions, a latch adapted to retain said members in their upper position, a crank upon said truck, a connecting

rod connecting said scoop and said crank, the whole organized to effect by the angular movement of said crank, a movement of said scoop and said members from their lower to their upper positions and vice versa when 55 said members are not latched in their upper positions and effect a dumping of said scoop upon its trunnions when said members are latched in their upper positions.

10. A scoop car comprising a wheeled truck, arms N pivoted to the forward end of said truck, a scoop L trunnioned upon said arms, cranks J mounted to revolve on said truck, connecting rods K pivoted to said scoop and said crank, and latches Q adapted 60 for latching engagement with said arms, substantially as described.

11. A scoop car comprising a wheeled truck, arms N pivoted to the forward end of the truck, a scoop L trunnioned upon said 70 arms, cranks J mounted to revolve on said truck, and connecting rods K pivoted to the scoop and to the cranks; substantially as described.

12. A scoop car having a low center of 75 gravity, comprising in part the combination with a low lying truck body having supporting wheels and axles adjacent the ends thereof, of a crank journaled low upon said body to rotate in a vertical plane within the space 80 between said axles, a rocking frame pivoted upon the forward end of said body, a scoop trunnioned upon said rocking frame and adapted to assume therewith a lower and an upper position, means for locking said frame 85 in its upper position to said body, and a connecting rod directly connecting said crank and said scoop, the rotation of said crank effecting movements of said scoop with said frame to and from said upper and lower positions when said frame is free, and 90 tilting said scoop on said frame when said frame is locked in its upper position.

In testimony whereof we affix our signatures, in presence of two witnesses.
